UNITED STATES PATENT OFFICE.

WILLIAM A. HEIDE, OF DETROIT, MICHIGAN.

SPARK PLUG.

Application filed June 10, 1920. Serial No. 387,972.

To all whom it may concern:

Be it known that I, WILLIAM A. HEIDE, a citizen of the United States, residing at Detroit, in the county of Wayne and State of Michigan, have invented a new and useful Spark Plug, of which the following is a specification.

This invention relates to spark plugs, one of its objects being to provide means whereby the accumulation of carbon between the electrodes can be prevented by setting up an intermittent circulation of air or gas between the electrodes, such circulation being effected by the movement of the piston within the cylinder of the engine.

A further object is to provide simple and efficient means for holding the parts of the plug assembled, one of the electrodes being shiftable relative to the other and having improved means for electrically connecting one of the terminals thereto.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a section through a spark plug constructed in accordance with the present invention.

Figure 2 is a plan view of one of the terminals.

Referring to the figures by characters of reference 1 designates the metal shell of the spark plug provided with an interior annular shoulder 2 and with an interiorly threaded end portion 3 adapted to be engaged by the usual type of packing nut 4. A porcelain core 5 is seated in the shell and held therein by the nut 4, this core being provided, at its upper end, with an angular extension 6 while projecting radially from the core between this extension and the nut 4 is a nose 7. A passage 8 is extended longitudinally from the inner end of the core 5 and terminates, opposite the nose 7, in a lateral extension 9 which is formed in the nose. Thus there is provided a continuous passage from the inner end of the porcelain core to

the external atmosphere. A bore or reduced passage 10 is formed in the extension 6 and in line with the center of the passage 8.

The metal shell 1 projects beyond the inner end of the core 5 so as to form one electrode of the spark plug. A rod 11 is extended longitudinally within the passage 8 and through the bore 10, this rod being provided at its inner end with a conical head 12 constituting the other electrode and which head is normally seated upon the flared lower or inner end 13 of the passage 8 so as to close said passage. A centering spider 14 or the like may be attached to the rod 11 so as to keep said rod properly positioned within the passage.

One end of the rod 11 projects through and beyond the extension 6 and is screw threaded, as shown at 15. Mounted on the extension 6 is a terminal plate 16 the corners of which are offset, as at 17 so as to straddle the extension 6 and prevent the plate from sliding out of position. This terminal plate has a central opening 18 from the wall of which are struck fingers 19. A coiled spring 20 bears on the plate 16 and is held properly centered by the fingers 19. This spring is housed within a cap 21 and a nut 22 which engages the threaded end 15 of the rod bears on the cap. By means thereof the tension of the spring can be controlled and the electrode 12 can be caused to bear upon its seat 13 with any desired degree of pressure. One of the conducting wires has been indicated at 23 and is suitably connected to the terminal plate 16.

It will be understood that when the spark plug is in place the suction created by the piston will intermittently unseat the electrode 12 and at the same time will set up a current of air through the passage 8 and its extension 9, this current as well as the movement of the electrode 12 relative to the seat 13, serving to loosen and remove any carbon that might otherwise accumulate between the electrodes. The spring 20 and the parts engaged thereby insure a constant connection between this movable electrode and the terminal plate 16. This spring also constitutes means whereby the pressure of the electrode upon its seat can be governed.

Obviously instead of opening the passage extension 9 directly to the external atmosphere, it can be connected to the intake manifold of the engine so that each time the electrode 12 is unseated and a suction is set up,

a small amount of fuel will be drawn into the engine. 20

If preferred the passage extension 9 can be connected with a suitable source of hot 5 air such as a jacket housing the exhaust pipe of the engine. In this manner heated air can be supplied to the engine through the spark plug. 25

For the purpose of limiting the movement of the electrode 11 so that the valve 10 12 will not open too far, an adjusting nut 24 can be mounted on the rod 11 and be secured by means of a lock nut 25.

What is claimed is:

15 The combination with a spark plug having an air supply passage opening therethrough and an electrode slidably mounted in the passage and normally closing it, of a terminal plate mounted on one end of the

spark plug and having offset portions straddling said end to hold the plate against rotation relative to the plug, a cap adjustably mounted upon the projecting end portion of the electrode, and a coiled spring housed within the cap and bearing on the terminal plate for holding the electrode in normal or closed position and for making an electrical connection between the terminal plate and the cap and electrode, and upstruck portions on the plate projecting into one end 30 of the spring. 30

In testimony that I claim the foregoing as my own, I have hereto affixed my signature in the presence of two witnesses.

WILLIAM A. HEIDE.
